Inventor.

UNITED STATES PATENT OFFICE.

GEORGE W. HOLDEN, OF DAYTON, OHIO.

IMPROVEMENT IN BOOK-COVER PROTECTORS.

Specification forming part of Letters Patent No. **185,234**, dated December 12, 1876; application filed May 12, 1876.

To all whom it may concern:

Be it known that I, GEORGE W. HOLDEN, of the city of Dayton, State of Ohio, have invented an Improved Copy-Book-Cover Protector, of which the following is a specification:

The nature of my invention consists in forming a pocket of the inner folds for the purposes of retaining the leaves of copy-books, blotting-pads, or detached sheets of paper.

The figure is an inside view of the cover.

The two end flaps C C are folded inward onto the body A to a point near the center. At the bottom are formed two narrow flaps, E E, which fold over onto the side flaps, to which they are made to adhere by any suitable preparation. At E (dotted lines) is shown

one of the lower flaps before folding. Thus are formed pockets for the leaves of a copy-book, blotting-pad, or detached sheets of paper. At D is shown the blotting-pad in proper position.

The cover-protector is made of any suitable paper, and, thus constructed, is a convenient and useful appendage to a copy-book.

What I claim as my invention is—

The pockets in a copy-book-cover protector, opening at the top and formed by the body of the cover and the joined side flaps C, and the bottom flaps E, for the purposes set forth.

GEORGE W. HOLDEN.
